UNITED STATES PATENT OFFICE.

RAYMOND A. WALTER, OF NEW YORK, N. Y., AND WALTER M. DAKE, OF FRANKLIN,
PENNSYLVANIA.

APPARATUS FOR USE IN THE CONSTRUCTION OF FRAMEWORK SUPPORTS FOR CONVEYERS.

Application filed February 4, 1924. Serial No. 690,513.

To all whom it may concern:

Be it known that we, RAYMOND A. WALTER and WALTER M. DAKE, citizens of the United States, residing, respectively, at New York city, in the county of New York and State of New York, and at Franklin, Venango County, State of Pennsylvania, have invented certain new and useful Improvements in Apparatus for Use in the Construction of Framework Supports for Conveyers, of which the following is a specification.

Our invention relates to apparatus for use in the construction of conveyers and while it is intended that it be used in the construction of conveyers for handling all kinds of material, it is particularly adapted for use in construction of conveyers used in mining and transporting coal.

An object of our invention is to provide an improved framework for a conveyer.

Another object of our invention is to provide an improved support for a conveyer.

Yet another object of our invention is to provide an improved framework or support for a conveyer, which is open at one side to facilitate removal and replacement of the return chain flights or belt.

A still further object of our invention is to provide a framework or support, for a conveyer, which will be easily manufactured, light in weight and of great strength.

A still further object of our invention is to provide an improved support, for a conveyer, which will make it more readily extensible inasmuch as its open side or end permits insertion or removal of parts of the conveyer without cutting, breaking or taking apart the lower conveying element whether chains, flight or belt.

In constructing portable extensible conveyers, such as those commercially known as the Claghorne type, it is customary to build a supporting framework having vertical members on both sides of the moving conveying members. These vertical members are joined by horizontal members at top and bottom, these horizontal members forming the supports for the upper and lower members respectively of the moving conveying element.

This type of framework is costly to build and is unsatisfactory in operation.

If the lower conveying element, or that

contained within and moving in the rectangular framework of horizontal and vertical supports, breaks or becomes worn, much time is lost in making repairs because it is extremely difficult to work in the restricted space, and the continuous broken or worn element can be removed, or a new one inserted, only by passing it longitudinally through frame after frame the entire length of the conveyer.

Also when it is desired to extend an extensible conveyer of the usual type by the insertion of additional unit frames at any given point, the same disadvantage appears and it becomes necessary to cut, break or open the upper and lower conveying elements. Another section of framework is then inserted and sections of conveying elements inserted and reconnected ready for use.

These operations consume much time and are very expensive. It is to overcome their disadvantages that this invention was conceived.

Our improved support is made in such shape that it has an open side, and is generally formed of metal bent into U-shape. When our support is used, the lower conveying element can be lifted out of its guides, drawn out to one side, repaired and replaced with small delay as compared with similar work using present supports.

In like manner if desired to insert or remove interior sections of a conveyer using our improved supports, a section can be taken out or one can be inserted without disconnecting or cutting the lower conveying element, or without being obliged to remove it longitudinally through the entire conveyer supports. Moreover, our improved support is sturdy, simple and economically manufactured.

With these and other objects in view which may be incident to our improvements, the invention consists in the parts and combinations to be hereinafter set forth and claimed, with the understanding that the several necessary elements comprising our invention, may be varied in construction, proportions and arrangement, without departing from the spirit and scope of the appended claims.

In order to make our invention more

clearly understood, we have shown in the accompanying drawings means for carrying the same into practical effect, without limiting the improvements in their useful applications to the particular constructions, which for the purpose of explanation, have been made the subject of illustration.

In the drawings:

Figure 1 is a view in side elevation showing a portion of a conveyer using our improved supports;

Fig. 2 is a cross sectional view on line 2—2 of the conveyer in Fig. 1, looking in the direction of the arrows;

Fig. 3 is a perspective view of our improved conveyer support.

Referring to the drawings for a detailed description, we have shown an upper conveyer element 1 and a lower conveyer element 2. The upper conveyer element is adapted to travel in a pan 3 forming a flat bearing surface and having upstanding sloped sides 4 to prevent loss of material carried by the conveyer. The pan is made in sections, and the sections are joined by splicing devices 5. In the present instance, the splicing devices comprise metal plates which follow the exterior contour of the pan sections, and which overlap the adjacent ends of the sections. The splicing devices 5 are fastened to adjacent pans by means of bolts or rivets 6.

The lower conveyer element 2 is ordinarily not adapted to carry material, but is necessary for the return of the conveyer elements to the positions in which the load may be added. Therefore, it is not necessary to have a pan structure such as is shown for the upper conveyer element. The lower conveyer element is adapted to run in guides 7 having upstanding sides 8. The upstanding sides 8 are only of sufficient height to prevent lateral displacement of the conveyer element 2. To join the sections of the guides, there are provided splicing members 9 which, in the present instance, comprise metal plates which fit against the upstanding walls 8 of the guides 7, and across the bottom thereof, and which are fastened by means of suitable bolts or rivets 11.

To support the pan 3 carrying the upper conveyer element 1, and the guides 7 carrying the lower conveyer element 2, we have shown conveyer supports 12 which, in the present instance, we form of I-beam, as I-beam construction is very strong and forms a flat surface both at its top and bottom by reason of the flanges. The support 12 comprises an upper horizontally extending arm 13, and a lower horizontally extending arm 14. The upper and lower horizontally extending arms are connected by a link 15, which is formed by bending the structure of the I-beam. Thus, the whole support takes somewhat the shape of a U laid on its side.

The upper support 13 is provided with apertures 16 in the flanges of the upper surface of the I-beam. The lower support 14 is likewise provided with holes 17 drilled in the flanges of the top surface of the I-beam. The pan 3 is adapted to be fastened by means of suitable rivets or bolts 18 to the top surface of the upper horizontal arm 13 by passing suitable bolts or rivets through the holes 16. The guides 7 are likewise fastened by means of suitable bolts or rivets 19, which pass through the holes 17 in the upper surface of the lower horizontal arm 14 of the support.

In operation, our type of support for the conveyer permits upper and lower sections of the conveyer to be readily removed for repair or replacement by reason of the fact that it is possible to lift sections of the conveyer bodily out of the lower guides. This feature is of great advantage also in lengthening or shortening the conveyer, where sections of the upper and lower elements can be easily and quickly removed. By reason of the fact that the supports for the conveyer allow ready access to and removal of conveyer elements, the labor and expense of repairing, replacement and changing the length of portable conveyers is greatly minimized.

While we have shown and described the preferred embodiment of our invention, we wish it to be understood that we do not confine ourselves to the precise details of construction herein set forth, by way of illustration, as it is apparent that many changes and variations may be made therein, by those skilled in the art, without departing from the spirit of the invention, or exceeding the scope of the appended claims.

We claim:

1. In a conveyer framework, an upper supporting platform, lower supporting guides, and supports therefor comprising unitary structures having horizontally disposed arms.

2. In a conveyer element, an upper supporting pan, lower supporting guides, supports therefor comprising horizontally disposed supporting arms, and connecting framework on one side only.

3. In a conveyer framework, upper supporting pan sections, splices therefor, lower supporting guides, splices therefor, supports comprising horizontally disposed supporting arms, and connecting framework on one side only.

4. In a conveyer framework, an upper supporting platform, a lower supporting platform, supports therefor comprising beams bent to form horizontally disposed supporting arms, and connecting links on one side only formed from the bodies of the beams themselves.

5. In a conveyer framework, upper sup-

porting pan sections, splices therefor, lower supporting guides, splices therefor, supports comprising beams bent to form horizontally disposed supporting arms, and connecting links on one side only formed from the bodies of the beams themselves.

6. A support for conveyers comprising in an integral structure, an upper supporting arm, a lower supporting arm, and a **U**-shaped connecting link on one side only.

7. A support for conveyers comprising in a unitary structure formed of a single metallic beam, a horizontally disposed upper

arm, a horizontally disposed lower arm, and a connecting link on one side only. 15

8. A support for conveyers comprising in a unitary structure, a horizontally disposed upper arm, a horizontally disposed lower arm, and a connecting link on one side only, said unitary structure being bent from the 20 body of a beam.

In testimony whereof we affix our signatures.

RAYMOND A. WALTER.
WALTER M. DAKE.
